UNITED STATES PATENT OFFICE.

JAMES O'SULLIVAN, OF LOWELL, MASSACHUSETTS.

FOOT-MEASURER.

1,010,451.

Specification of Letters Patent.

Patented Dec. 5, 1911.

Application filed April 19, 1909. Serial No. 490,687.

To all whom it may concern:

Be it known that I, JAMES O'SULLIVAN, a citizen of the United States, residing at Lowell, in the county of Middlesex and State of Massachusetts, have invented certain new and useful Improvements in Foot-Measurers; and I do hereby declare the following to be a full, clear, and exact description of the invention, such as will enable others skilled in the art to which it 5 pertains to make and use the same.

The present invention relates to an improvement in foot measurers.

The object of the invention is to produce 15 a contrivance for measuring the length, width and curvature of the arch of the foot, which is simple in construction and convenient for use.

To this end the invention consists of the 20 foot measurer hereinafter described and set forth in the claims.

In the accompanying drawings illustrating the preferred form of the invention, Figure 1 is a plan view of the foot measurer; Fig. 2 is a vertical section taken on the line 2—2 in Fig. 1; Fig. 3 is a transverse vertical section taken on the line 3—3 in Fig. 1.

The frame or base 1 is made of wood and 25 is, generally speaking, rectangular in shape, being widened somewhat at 2, the place approximately where the ball of the foot comes. At this point a foot centering device is provided, which also acts as a width gage. This width gage comprises two oppositely disposed slides 4 and 6 provided with depending portions 8 and 9 which are adapted to slide in a groove 10 extending transversely across the frame. The portions 8 and 9 are 30 screw-threaded to coöperate with a shaft 11 having right and left hand screw-threaded portions 12 and 13, and which is journaled in a bearing 14. The shaft 11 is prevented from moving transversely of the frame by 35 means of collars 16 secured thereon and bearing against the opposite faces of the bearing 14. The slides 4 and 6 pass over plates 18 and 20 which are suitably secured to the upper face of the frame 1 on opposite 40 sides of the groove 10. The plate 20 is provided with a gage or index to indicate the width of the foot. The front end of the frame or base is provided with a toe gage 45 against which the toe of the person is rested when the device is applied to the foot. This toe gage is provided with a rearwardly

extending shank 24 which is received in a groove 26 extending longitudinally of the base. The toe gage is secured in its adjusted position by means of a clamping screw 27 which is adapted to bear against the shank 24. The upper face of the shank 24 is provided with a series of numbers and spaces indicating the length of the foot. The heel end of the base is provided with a heel gage 30 which comprises a curved plate having a rearwardly extending shank 32 which is received in a gage holder 34 through which it is adapted to be moved for adjustment to the size of the foot, and in which it is adapted to be secured by a thumb screw 35.

The arch measuring device comprises two parallel springs 40 and 41 which are secured at their front ends by means of rivets to the 75 plate 18. The rear ends of the springs are arranged to slide in a slot 42 formed in the upper face of the base 1, and are retained within said slot by a plate 44 attached to the base by means of screws. The springs 80 40 and 41 are formed with depending portions 46 and 47 respectively, which form abutments for the adjusting screws 48 and 49. These screws are threaded for a portion of their length to coöperate with a threaded plate 50 secured to the rear end of the base 1.

Depending from the under side of each spring 40 and 41 is a gage 52 which indicates the height of the spring above the base for any particular arch. It is sometimes necessary to vary the arch at the anterior and posterior portions. Accordingly, adjusting screws 54 and 55 are provided for varying these portions of the arch, said screws being threaded through plates 56 and 57 respectively, which are set into the top face of the base 1 and extend transversely across the base. When the adjusting screws 48 and 49 are tightened the springs 40 and 41 are arched upwardly. The several adjusting devices secure a close approximation of the arched springs to the arch of the foot.

In use the device is placed against the foot with the ball of the foot within the centering device or width gage. The heel gage is then brought into contact with the heel of the foot and the toe gage into contact with the toe, and each is secured in adjusted position. Thereupon, either of the screws 48 or 49 is tightened, according as the right or left foot is being measured.

Or both of the screws 48 and 49 may be tightened separately to independently bend up the arch measuring springs and measure the form of the arch on both the inner and outer sides of the foot. The particular screw is tightened sufficiently to cause the corresponding spring to fit the arch, and the height of this spring is indicated by the gage 52. If it is necessary to vary the anterior or posterior portions of the arch the screws 54 and 55 may be adjusted accordingly.

The important features of this invention reside in the fact that the springs, being held at both ends, are caused to bend in a manner corresponding to the curvature of the foot, and that the device can be used on the foot without having the person stand on it. This latter is a valuable feature, because when the person with a weak or broken arch stands on his foot, the arch is distorted and an accurate measurement of the arch at this time would be useless, as it would not indicate the curvature which the arch support should have. With this device a foot retaining its normal shape can be measured without being subjected to the distortion due to standing on the foot. Furthermore, the correlation of the centering device with the arch measuring springs is such that one foot is properly positioned upon the base when the ball of the foot is located within the centering device.

The two arch measuring springs and their several respective adjusting devices accurately measure the form of the arch on both sides and on either foot.

The invention is susceptible of embodiment in other forms within the scope of the following claims:

1. A measuring device, having, in combination, a frame, a length measuring device, a foot centering and width measuring

device, and a pair of arch measuring springs arranged to be distorted independently, substantially as described.

2. An arch measurer, having, in combination, a frame, an arch measuring spring, means for distorting the spring to fit the central arch, and means for adjusting the spring to fit the anterior and posterior arch, substantially as described.

3. An arch measuring device, having, in combination, a frame, a heel gage longitudinally adjustable on the frame, a toe gage longitudinally adjustable on the frame, a foot centering and width measuring device mounted on the frame between the heel and toe gages, comprising two laterally movable slides adapted to engage the opposite sides of the foot, a pair of arch measuring springs mounted on the frame between the heel gage and the foot centering and width measuring device arranged to be distorted independently, and a gage connected to each spring for indicating the amount of its distortion, substantially as described.

4. An arch measurer, having, in combination, a frame, an arch measuring spring secured at one end to the frame, mechanism comprising a thumbscrew for pressing against the free end of the spring to distort the spring by end pressure to fit the central arch, and two thumbscrews threaded in the frame beneath the anterior and posterior arch portions of the spring respectively and adapted to be turned against the bottom surface of the spring for adjusting the spring to fit the anterior and posterior arch, substantially as described.

In testimony whereof I affix my signature, in presence of two witnesses.

JAMES O'SULLIVAN.
